UNITED STATES PATENT OFFICE

WILLIAM M. BARKER, OF CANTON, OHIO

PNEUMATIC SEPARATOR

Application filed April 20, 1926. Serial No. 103,281.

The invention relates to separators for use in brick, tile and other clay and shale working plants, and also in ore and other milling plants, where material is ground and reduced 5 in a dry or partially dry state to a specified fineness.

In such plants grinding machines are usually used to grind rock or lump material, and it has been found necessary heretofore 10 to use screens to separate a desired size of material discharged from the grinding machines, from over-size material mixed therewith, and to return the over-sized material back to the grinding machines for regrind- 15 ing.

Such screens have been found to be very troublesome in plant operation. They blind and clog and the screen wires break, making them uncertain in action, so that they re- 20 quire constant watching and attention.

To overcome the various difficulties with screens, many different kinds and shapes of mechanically operated screening devices have been designed, but such mechanically operated screening devices have not eliminated 25 the imperfections inherent in screens in general for fine sizing or separating of dry or partially dry material.

It is generally the object of users of such 30 devices to constantly increase the tonnage of material of a desired constant fineness which is processed through the separators in their plants.

Screens in general, however, have been 35 found so ineffective that it is quite common experience to find that 50% to 75% of material, that is already fine enough and should pass through the screens ready for the next 40 step in the manufacturing process being undertaken, actually passes over the screens as oversize and is returned to the grinding machines for regrinding.

This constant recirculation of material 45 actually fine enough for use, causes an extra and large circulating load to pass through the grinders and elevators, and necessitates an extra consumption of power to operate the grinders and elevators as well as the separators.

Moreover, fines that are returned to the

grinders due to the ineffectiveness of screening devices, cushion and retard the grinding action of the grinders on coarse material.

The objects of the present invention are to completely separate material of any desired 55 fineness from a stream of material as discharged from a grinding machine as by the use of an elevator; and these objects are attained by subjecting a preferably vertically falling stream of material as discharged 60 from the top or head of an elevator to a preferably horizontal cross current as of air which, depending upon its pressure, carries material of a certain fineness with it and permits coarser material to drop as into the intake 65 of a grinding machine for further grinding and reduction in size.

Further objects of the invention are to provide a device which is simple and compact in construction and is provided with ample 70 clearance at all points for undersized or unseparated material to drop freely by gravity down through a separating box, and so arranged that even damp material will not build up and clog the device.

A preferred form of apparatus for attaining these and other objects by the means set forth aforesaid in general terms, is illustrated in the accompanying drawings forming part 75 hereof in which—

Figure 1 is an elevational view of a preferred apparatus embodying the invention, portions of the outer case walls being broken away to more clearly illustrate the interior construction of the device; and

Fig. 2, a vertical cross section thereof, as on line 2—2, Fig. 1.

Similar numerals refer to similar parts throughout the drawings.

The improved pneumatic separator indicated generally at 10, includes walls forming a separating chamber 11, and a separator inlet 12 including an upper inclined duct 12a communicating with a lower and preferably vertically directed baffle chamber 12b which 95 communicates as at the junction 12b' with the separating chamber 11.

The separating chamber preferably includes upper inclined walls 11a and 11b inclining downward and flaring outward 100

from their connection with the baffle chamber 12b, a lower inclined and angled wall 11c having the general inclination of the wall 11a and including an upper section 11c' of one slope and a lower section 11c'' of a greater slope, a preferably vertical wall 11d laterally offset a substantial distance from the axis of the baffle chamber 12b, which distance is preferably greater than the width *w* of the baffle chamber, together with end walls 11e and 11e'.

The wall 11b and the upper portion 11c' of the angled wall 11c, converge to communicate with an inclined outlet 13 for separated material or fines of a proper size, and the lower portion 11c'' of the angle wall 11c converge to communicate with a preferably vertically directed outlet 14 for discharging oversize material as to the inlet of a grinding machine. The outlet 14 is preferably laterally offset a substantial distance from the inlet baffle chamber 12b, for purposes hereinafter to be described in detail.

The separator inlet 12 communicates with a preferably downward depending outlet 15 at the top or head of an elevator case 16 in which is operatively mounted an elevator as a bucket elevator 17, which lifts unseparated material M which may be discharged from a grinding machine, to the elevator head or top at 18, and delivers said unseparated material into the separator inlet 12 through the outlet 15.

The separator inlet 12 as aforesaid may preferably include a duct 12a inclining downward and flaring outward from its connection as at 19 with the elevator case outlet 15, and the duct 12a communicates with the preferably vertically directed baffle chamber 12b provided with a plurality of spaced and oppositely inclined baffle platforms 20 and 20' for evenly spreading out material passing through the separator inlet into a thin, wide, vertically falling stream.

Opposite the outlet 13, the separating chamber is provided with a plurality of substantially horizontal nozzles 21a, 21b and 21c extending preferably across the whole width of the separating chamber, the nozzle outlets being preferably stepped with each other, that is to say, the nozzle 21b extends into the separating chamber beyond the nozzle 21a, and the nozzle 21c extends into the separating chamber beyond the nozzle 21b.

The nozzle 21a is preferably in the form of a relatively narrow horizontal slot in the wall 11d, adjacent the junction of the inclined wall 11a and the wall 11d, and the nozzle 21a is thus located a substantial distance below and to one side of the junction 12b' of the vertically directed baffle chamber 12b and the separating chamber 11.

For deflecting upwards a current of air entering the chamber 11 through the upper nozzle 21a, a preferably horizontal deflector plate

P1 extends from the lower edge of the nozzle 21a into the chamber 11 to a junction as at J1, with a preferably vertically extending plate P2 preferably in line with the wall 12b' of the baffle chamber 12b, next adjacent the wall 11d of the separating chamber.

The nozzle 21b is preferably formed by a horizontal slot in the wall 11b spaced below the nozzle 21a, and communicating with preferably horizontal upper and lower plates P3 and P4 extending into the chamber 11 beyond the vertical wall P2, and to the end J2 of nozzle 21b, and the lower plate P4 making a junction at J2 with a preferably vertically extending plate P5.

The nozzle 21c is preferably formed by a horizontal slot spaced below the slot for the nozzle 21b in the wall 11b, and communicating with preferably horizontal plates P6 and P7 extending into the chamber 11 beyond the wall P5, to the end J3 of the nozzle 21c.

The vertical plate P2 preferably extends to connect with the upper horizontal plate P3 of the nozzle 21b and the plate P5 preferably extends to connect with the upper plate P6 of the nozzle 21c, and the junction J1 and the ends J2 and J3 of the nozzles 21b and 21c are preferably substantially located in a plane making an angle of substantially sixty degrees with the plate P7.

The lower plate 11c of the separating chamber 11 is angled as at 11c''' below the outer end J3 of the nozzle 21c to form the aforesaid upper portion 11c' of one slope and the portion 11c'' of a greater slope for reasons hereinafter to be set forth.

The nozzles 21a, 21b and 21c communicate with the outlet 22 of a blower 24, which is suitably mounted and connected with a motor, not shown.

The separating chamber may be provided with an internal adjustable gate 25 preferably horizontally hinged at the top of the chamber as at 26 and provided with an outwardly extending bolt 27 passing through the forward upper inclined wall 28 of the chamber, upon which is screwed the adjustable wing nut 29 for varying the area of the communication between the chamber 11 and the outlet 13 for the material or fines F separated from the material M to the proper size by the action of the device. The over-size material O from which the fines F have been separated by the action of the device, pass down through the outlet 14 as aforesaid.

The operation of the device consists essentially of dropping mixed material M, containing fines F of a desired size and over-size material O, through the duct 12a of the inlet orifice 12 into the baffle chamber 12b where it is evenly spread out into a thin, wide, vertically falling stream which passes in front of the substantially horizontal nozzles 21a, 21b and 21c.

The blower 24 being in operation, rela-

tively thin horizontal blasts of air are directed into the separating chamber 11 as cross currents passing through the vertically falling stream of unsized material M.

The nozzle 21a having its end located in the wall 11d, laterally offset a substantially distance from the junction 12b' of the baffle chamber 12b with the separating chamber 11, directs an upper blast of air into the separating chamber which is deflected upwards by the deflector plate P1 for first winnowing or fluffing the vertically falling material M, which is next subject to the substantially horizontally directed blast issuing from the end J2 of the nozzle 21b, located substantially directly under the vertically directed baffle chamber 12b, and it has been found that the blast from the nozzle 21b operating upon the material M fluffed by the upwardly deflected blast from the nozzle 21a, performs a major portion of the actual separating action of the device.

For completely accomplishing the desired separation, the stream of material is next subject to the substantially horizontally directed blast issuing from the end J3 of the nozzle 21c, located in the chamber 11 as aforesaid, beyond the ends of the upper nozzles 21a and 21b, and the junction J1 and the ends J2 and J3 of the nozzles 21b and 21c being as aforesaid preferably located substantially in a plane making an angle of substantially sixty degrees with the plate P7.

It will be seen that as the respective air blasts leave their restricted nozzle chambers and enter into the relatively large separation chamber 11, said air blasts will become suddenly expanded, thereby increasing their effective area upon the stream of falling material. It is therefore necessary to maintain a substantially constant distance between the nozzle outlets and the material stream in order to obtain the required effective pressure in each air blast upon the material stream. This is accomplished by locating the nozzle outlets in stepped relation with each other, as above described.

The falling stream then impinges upon the upper portion 11c' of the angle plate 11c, and the slope of the portion 11c' is preferably relatively gradual, so that the material falling upon it will slide thereover with a relatively slow speed, in order that the full effect of the blast from the nozzle J3 may be attained for completely separating the fine material F from the oversize material O.

After the oversize material O has slid over the junction 11c''' of the angle plate 11c upon the relatively steeper lower portion 11c'', the vertical velocity of the oversize material is increased with reference to the velocity of the material sliding over the upper portion 11c', thereby enabling a rapid removal of the oversize once it has been

separated from the fine by the action of the three stepped blasts.

The oversize material O slides over the relatively steep portion 11c'' of the lower angle plate 11c into the oversize outlet 14, 70 which may be connected with a grinder inlet for regrinding the oversize.

By the arrangement of the plates P6 and P7 extending into the chamber 11 over the oversize outlet 14 to their end J3 substantially above the junction 11c''' of the angle plate 11c, and by the lateral offsetting of the oversize outlet 14 from the inlet 13, and by the inclination of the fine outlet 13, no air leaves the chamber through the oversize outlet 14, and there is in fact a slight vacuum in said oversize outlet 14 during the operation of the device, thereby facilitating complete separation.

It has been found by actual operation of the apparatus, that the particular arrangement of the walls of the chamber 11, the inlets and outlets therefor, and the offset and stepped nozzles therein, heretofore described in detail, enable the most satisfactory and efficient operation.

The size of the fines F recovered from the falling unsized material M, depends solely upon the pressure of the cross current air.

In tests made with apparatus embodying the invention as aforesaid, it has been found that only a slight pressure of cross current air is required to be delivered by the blower through the horizontal nozzles, because this air does not have to lift or divert the whole of the material M as delivered from the elevator, since the heavy over-size O drops by gravity past the air nozzles and is unaffected by the cross currents. The cross current air delivered from the separating nozzles is used only to divert into the fine outlet 13 the material that is of the predetermined fineness as fixed by the pressure of the currents.

When the air jet pressure is determined by trial for separating fines F of a given size, from unsized material M, and the regulation of the blower and the adjustment of the gate 25 have been made and set, this separating pressure is delivered through the nozzles continuously and on more attention is required for the apparatus excepting to maintain the cross current air pressure constant by suitable regulation of the blower motor, or otherwise.

Should another size of fine be desired at any time, it may be readily obtained by merely changing the blower fan speed, or by throttling the flow of air by means of a suitable gate on the fan intake, or in the delivery pipe from the fan to the nozzles.

It has been determined by experience with operations of the apparatus that an air pressure of $\frac{1}{10}$ inch water gauge is amply sufficient to separate $\frac{1}{4}$ inch material such as shale, clay, and limestone, from a falling

stream of unsized material; and for fines of a size of minus 12 mesh, good results may be obtained with as low a pressure as $\frac{1}{10}$ inch water gauge.

5 The low air pressures required by the device for operation, necessitates the use of power materially less than that required to run usual types of mechanically operated screens.

10 It has also been determined that the apparatus provides a clean separation, and that in practice the fines going back with the oversize for regrinding is not more than 2%. This is much less as aforesaid than the percentage of fines redelivered to the grinding machines by screening devices of equal capacity.

15 The apparatus will also handle material containing water, and so damp that it would at once clog up and coat over usual types of screen. The device will process without difficulty material as damp as it is desirable to run through ordinary dry pans. Consequently by the use of the apparatus, clay 20 and shale may be dampened at the pans to prevent dust rising and escaping from the grinders.

25 Since such a small quantity of separating air is required for operating the apparatus, the fines may be conducted from the separator direct through pipes to closed storage or feed bins, provided with vent pipes, without serious loss of dust.

30 Likewise, the entire plant may be rendered practically dustless, either (1) by running a pipe from the suction inlet to the fan into the top of the drying rooms as of a brick plant, so that the moisture from these rooms may be utilized in the apparatus, or (2) a 35 steam or water spray may be arranged to settle the dust in the receiving bins, or (3) water or steam vapor may be automatically fed in at the suction inlet of the fan in sufficient quantity to dampen the material being processed, so that no dust arises in the bins.

35 Each of the above methods of providing for dustless plant operation have been found to be practical by actual operation of the device herein, arranged as aforesaid.

40 A further advantage of the present apparatus is its compact size, by which less plant space is required than is required for screens of equal capacity, permitting the present device to be installed in part of the space now occupied by screening devices, and releasing 45 floor space for other uses.

45 In the construction of new plants, plant lay-out and the plant flow sheet may be materially simplified and improved by the use of the present apparatus, enabling the elimination of conveyors, and the attainment of a substantially dustless plant.

50 In addition to the foregoing uses, the device is adapted for cleaning coal from a mix-

ture of coal and slate. That is to say the mixture M may consist of coal F and slate O, and the coal F may be removed from mixture as heretofore described.

I claim:—

1. The method of separating unsized material into fine material and oversize material, which includes subjecting a single stream of freely falling unsized material to successive suddenly expanding currents of fluid such as air for diverting the fine material from the stream to another stream, each successive current of fluid suddenly expanding at a position horizontally offset from the position of sudden expansion of the preceding current to compensate for the horizontal displacement of the material stream due to the effect of the preceding current. 70

2. The method of separating unsized material into fine material and oversize material, which includes subjecting a single stream of freely falling unsized material to successive suddenly expanding currents of fluid such as air of equal pressure for diverting the fine material from the stream to another stream, each successive current of fluid suddenly expanding at a position horizontally offset from the position of sudden expansion of the preceding current to compensate for the horizontal displacement of the material stream 75 80

due to the effect of the preceding current. 85

3. The method of separating unsized material into fine material and oversize material, which includes subjecting a single stream of freely falling unsized material to successive suddenly expanding currents of fluid such as air in a single chamber for diverting the fine material from the stream to another stream, each successive current of fluid suddenly expanding at a position horizontally offset from the position of sudden expansion of the preceding current to compensate for the horizontal displacement of the material stream 90 95

due to the effect of the preceding current. 100

4. Apparatus for separating unsized material into fine material and oversize material, which includes means for creating a single stream of freely falling unsized material, walls forming a separating chamber in the path of the material stream, vertically spaced horizontally directed air nozzles communicating with said chamber, the successive nozzles being horizontally offset for maintaining a substantially constant distance between the material stream and each nozzle, and 105 means for supplying a current of air to each nozzle. 110

5. Apparatus for separating unsized material into fine material and oversize material, which includes means for creating a single stream of freely falling unsized material, walls forming a separating chamber in the path of the material stream, vertically spaced horizontally directed air nozzles communicating with said chamber, the successive nozzles 115 120 125

130

zles being horizontally offset for maintaining a substantially constant distance between the material stream and each nozzle, means for supplying a current of air to each nozzle, and an outlet for the fine material substantially horizontally opposite the air nozzles.

5 In testimony that I claim the above, I have hereunto subscribed my name.

WILLIAM M. BARKER.
